United States Patent Office.

JACOB BEESLEY, OF PHILADELPHIA, PENNSYLVANIA, ASSIGNOR
TO THOMAS J. CLOSE.

Design No. 3,594, dated August 3, 1869.

DESIGN FOR THE ARM-END OF A SETTEE.

The Schedule referred to in these Letters Patent and making part of the same.

To all whom it may concern:

Be it known that I, JACOB BEESLEY, of the city and county of Philadelphia, and State of Pennsylvania, have invented a new Design for an Arm-Settee, and of which the following is a full, clear, and exact description, reference being had to the accompanying drawings, making part of this specification.

Figure 1. A to A is the seat and back line, with an edge projecting over the outside, with lipped lugs on, to receive the slats completing the settee.

Figure 2. B is the arm, connecting in two different places with the back line of the settee, and extending in scroll-shape toward the front part of the seat, there connecting with a scroll of smaller size. The interior of scrolls forming the outlines of the arm is of a combination of French-style scrolls connected with the back line in one place, and extending across to the front scroll of arm, and also connecting with the top scroll of arm, thus giving strength and beauty to the arm.

Figure 3. C C is a combination of French-style scrolls, connecting with the seat and back line or margin, extending back and below the seat, and connecting in beautiful outlines to the base of feet-scrolls in the centre of said scrolls forming the combination. Below the seat-line is one of circular form with Gothic edge. Inside the flat, or outside, is a succession of small beads, connecting with, and extending to the front and back line, also below and across with French style scrolls, thus giving strength and beauty to the entire design.

What I claim as my invention, and desire to secure by Letters Patent, is—

The design for an arm-settee end, herein set forth.
